(57) **CLAIM**

The ornamental design for a "nasal dilator device", as shown
and described.

DESCRIPTION

FIG. 1 is a top, right perspective view of a nasal dilator
device in a closed condition.

FIG. 2 is a bottom, left perspective view of the nasal dilator
device of FIG. 1.

FIG. 3 is a top, plan view of the nasal dilator device of FIG.
1.

FIG. 4 is a bottom, plan view of the nasal dilator device of
FIG. 1.

FIG. 5 is a front view of the nasal dilator device of FIG. 1.

FIG. 6 is a rear view of the nasal dilator device of FIG. 1.

FIG. 7 is a right side view of the nasal dilator device of FIG.
1.

FIG. 8 is a left side view of the nasal dilator device of FIG.
1.

FIG. 9 is a top, front right perspective view of the nasal
dilator device of FIG. 1 in an open condition.

FIG. 10 is a front view of the nasal dilator device of FIG. 9.

FIG. 11 is a rear view of the nasal dilator device of FIG. 9.

FIG. 12 is a top, plan view of the nasal dilator device of FIG.
9.

FIG. 13 is a bottom, plan view of the nasal dilator device of
FIG. 9.

FIG. 14 is a right side view of the nasal dilator device of
FIG. 9; and,

FIG. 15 is a left side view of the nasal dilator device of FIG.
9.

1 Claim, 8 Drawing Sheets
